INTERFACE CABINET FOR TELEPRINTING

John P. Kennedy, Columbus, Ohio, assignor to
MI², Incorporated

Filed Mar. 21, 1973, Ser. No. 343,429

Term of patent 7 years

Int. Cl. D14—03
U.S. Cl. D26—14 R

FIG. 1

FIG. 3

FIG. 2

FIG. 4

FIG. 1 is a front perspective of an interface cabinet for teleprinting showing my new design;

FIG. 2 is a side elevation thereof;

FIG. 3 is a top plan view thereof; and

FIG. 4 is an end elevation thereof.

I claim:

The ornamental design for an interface cabinet for teleprinting, as described and shown.
